E. T. MILLER,
GEOMETRIC FIGURE,
APPLICATION FILED FEB. 11, 1919.

1,344,053.

Patented June 22, 1920.

UNITED STATES PATENT OFFICE.

EMMA THORNTON MILLER, OF SAN ANTONIO, TEXAS.

GEOMETRIC FIGURE.

1,344,053.

Specification of Letters Patent. Patented June 22, 1920.

Application filed February 11, 1919. Serial No. 276,438.

To all whom it may concern:

Be it known that I, EMMA THORNTON MILLER, a citizen of the United States, and a resident of San Antonio, in the county of Bexar and the State of Texas, have invented a new and useful Geometric Figure, of which the following is a specification.

My present invention relates generally to the aforesaid new and useful geometric figure which is to be hereinafter described, and more particularly, at the present time, to the use of the boundary lines of the said geometric figure for plotting and delineating a pattern for a covering for balls and spherical bodies.

Among various other useful and artistic objects of my invention, I aim to provide coverings for balls, and the methods for producing the patterns for the same, said coverings being so formed and disposed as to require a minimum length of closure, thus lessening the amount of sewing necessary for the complete closure of coverings over balls and the like.

Further objects and advantages of my invention will be better understood from the following description thereof, in which reference is made to the drawings forming a part of this specification, and wherein—

Figure 1 shows an outline of the said geometric figure, together with such subsidiary lines and marks as are useful in outlining the same, which outline indicates among other things, the pattern for the coverings for balls and spherical bodies.

Fig. 2 shows the covering as applied to a ball, the pattern having been laid on the reverse side of the material, in cutting the covering.

Reference is now made to Fig. 1. Starting with a straight line, 1, a second straight line, 2, perpendicular to the said line, 1, is made to intersect the said line, 1, as for instance at the point 3.

With a pair of compasses opened to span the necessary distance, as for instance, substantially to the extent of one third of the length of the diameter of the spherical body to be covered, one point of the said compasses may be and is placed on the intersection of the lines, 1 and 2, at 3, and the circumference 4 is made.

With the points of the compasses separated to the extent of the length of one radius and a fraction thereof, as for instance, one radius and a half of the circle

inclosed by the circumference 4, one point of the said compasses is placed at a point in one of the said radii, as for instance at 5 which represents the central point of the indicated radius, and the semi-circumference 6 is drawn between 7 and 8 and extended by a broken line between 8 and 7, making the circumference 4 tangential internally to the circumference 6, at 7.

With the points of the compasses separated to a distance corresponding to two radii and a fraction of a radius, as for instance, two radii and a half of the circle inclosed by the circumference 4, one point of the said compasses is placed at a point in one of the radii of the indicated circle, as for instance at 9, which represents the central point of the indicated radius, and the semi-circumference 10 is drawn between 8 and 11, and extended by a broken line between 11 and 8, making the circumference 6 tangential internally to the circumference 10 at 8.

Measuring from the center of the circle inclosed by the circumference 4, a point in the line 1 is located beyond the points 9, 7 and 11, by taking a length equal to a certain number of radii of the circle inclosed by the circumference 4, as for instance, six radii of the said circle, and a line 2' perpendicular to the line 1, is made to intersect the same at the said point, as at 3'.

With the points of the compasses separated to a distance corresponding to one radius of the circle inclosed by the circumference 4, one point of the same is placed at 3' and the circumference 4' is drawn.

With the points of the compasses separated to the extent of one radius and a fraction thereof, as for instance, one radius and a half of the circle inclosed by the circumference 4 or 4', one point of the said compasses is placed at a point in one of the radii of the circle inclosed by the circumference 4', as for instance at 5', which represents the central point of the indicated radius, and the semi-circumference 6' is drawn between 7' and 8', and extended by a broken line between 8' and 7', making the circumference 4' tangential internally to the circumference 6' at 7'.

With the points of the compasses separated to a distance corresponding to two radii and a fraction of a radius of the circle inclosed by the circumference 4 or 4', as for instance, two and a half radii of one of the

said circles, one point of the said compasses is placed at a point in one of the radii of the circle inclosed by the circumference 4', as for instance at 9', and the semi-circumference 10' is drawn between 8' and 11, and extended by a broken line between 11 and 8', making the circumference 6' tangential internally to the circumference 10' at 8'.

Using the intersecting points at 12 and 7,
10 a straight line is indicated between the two points, and extended to intersect the semi-circumference 10 at 13.

Similarly using the intersecting points at 12' and 7', a straight line may be, and is indicated between the said points, and extended to intersect the semi-circumference 10' at 13'.

Using the points 13 and 7', a straight line 14 is drawn between the said points.

20 Similarly using the points 13' and 7, a line 14' is drawn between the said points.

The geometric figure referred to in the subject of this application and in various paragraphs in the specification is indicated 25 and inclosed by the lines which include the points 7, 14', 13', 10', 8', 6', 7', 14, 13, 10, 8, and 6, and may be and is cut out along said lines and through the said points, thus among other possible uses, forming a pattern 30 for a covering for a ball or other spherical body.

Reference is now made to Fig. 2. In adapting the covering which may be and is cut by the pattern as indicated in the foregoing, to a ball or the like, the edges are perforated at intervals, substantially as shown, and are joined, beginning at the point 7 or 7', and continuing until the similar opposite point is reached,—or the join-

ing may begin at both points, 7 and 7', 40 allowing the final closure to take place at other points in the outline of the pattern or edge of the covering, as for instance, at points 10 and 10'.

To insure accurate and easy closure of the 45 covering as shown and described, over a ball or the like, holes at intervals are preferably provided for stitches, substantially as shown in the drawings which form parts of this specification. 50

I claim:—

1. A blank including an intermediate portion having straight parallel edges, and including oppositely disposed end portions having curved edges, the edge of each end 55 being formed on the arcs of circles of different diameters, the said end portions being symmetrical with respect to each other.

2. A blank including symmetrical end portions the edges of which are formed on 60 the arcs of relatively large and relatively small circles, and an intermediate portion having straight edges, each of which is tangent to one end of the edge of one end portion and forms an angle with the opposite 65 end of the edge of the opposite end portion.

3. A covering blank for base-balls, comprising an intermediate portion, and reversely disposed end portions having curved edges formed on the arcs of circles of different diameters. 75

4. A covering blank for base-balls, comprising a single length of material having curved end portions, and an intermediate portion disposed at an angle with respect to a vertical line which intersects the curved portions at corresponding points.

EMMA THORNTON MILLER.
